QUICK OPENING AND SEALING ENVELOPE

Benjamin M. Aldrich, Stillwater, Okla.

Application September 16, 1943, Serial No. 502,675

4 Claims. (Cl. 229—77)

This invention relates to an envelope and sealing means therefor, and pertains more particularly to an envelope of the two compartment type for use in carrying letters or other matter requiring different rates of postage, although the same is not restricted to such use.

The primary important object of this invention is to provide a device of the above character in which the several compartments thereof are formed from a single blank.

Another important object of the invention is to provide an envelope blank of the above character in which the means, such as an adhesive or the like, for securing the several parts thereof in their final or assembled form is placed upon one side only of the blank.

Another important object of this invention is to provide an envelope of the above character which is so folded and secured together that the cover flap thereof may be quickly sealed and then unsealed so as to permit a ready inspection of the contents of one or both of the compartments and to thereby afford a substantial saving of time both in the sealing and unsealing operations.

Another important object of this invention is to provide an envelope of the above character which permits of a temporary adhesive sealing of the closure flap and which at the same time admits of rapid inspection of the contents and a subsequent and rapid reclosing of the same.

A still further important object of this invention is to provide a temporary adhesive sealing of the envelope which will permit rapid opening thereof and a subsequent reclosing of the same by a part of the closure fastening means.

The foregoing and other important objects and advantages of the above named device will be readily apparent throughout the course of the following specification, claims and attached drawing, in which like reference characters denote like parts throughout the same and in which,

Figure 1 is a plan view of the blank from which the envelope is formed.

Figure 2 is a side elevation of the envelope before the body portion of the first class envelope is finally secured to the second-class envelope.

Figure 3 is a perspective view of the envelope shown in Figure 2.

Figure 4 is a perspective view of the envelope with the closure flap in partially open position.

Figure 5 is a fragmentary rear elevation of the envelope with the temporary adhesive sealing means in position about the usual metal envelope fastening means.

Figure 6 is a plan view of the temporary ad-

hesive sealing means, such as shown in Figure 5, and

Figure 7 is a modified form of temporary sealing means such as shown in Figures 5 and 6.

Referring in detail to the drawing, and more particularly to the preferred embodiment of the blank, as depicted in Figure 1, the same consists of a single sheet of suitable material which is formed to provide an envelope for containing first and second class mail matter. The portion of the envelope for containing second-class matter, consists of a body portion 1 having a side tab 2, a side sealing flap 3 and a bottom sealing flap 4. The side tab 2, side sealing flap 3 and bottom sealing flap 4 from continuations of and are defined from the body portion 1 by score lines 5, 6 and 7 respectively.

The first class mail matter receiving envelope consists of a body portion 8 having side portions 9 and 10 coated with an adhesive for a purpose to be hereinafter more fully described. The body portion 8 is connected to the body portion 1 by means of a connecting web or strip 11, the side edges 12 and 13 of which are spaced inwardly a predetermined distance from the score lines 5 and 6 of body portion 1 and from the adhesively coated areas 9 and 10 of the body portion 8. The lower and upper limits of the connecting web or strip 11 are defined by score lines 14 and 15 respectively.

Connected to the upper edge of the body portion 8, which is defined by the score line 16, is a closure flap 17. The closure flap 17 which is designed to seal both compartments of the envelope, in certain instances, is provided with a horizontally extending adhesively coated area 18 which is defined along its bottom edge by score line 16 and along its upper edge by score line 19.

The closure flap 17 is further provided above the area 18 with an adhesive coating 20 and with an opening 21, the latter to receive the bendable prongs 22 and 23 of the usual metal fastening member 24.

To form the compartment envelope from the blank thus far described, the side tab 2 is first folded over the body portion 1 along score line 5. Side sealing flap 3 is then folded over side tab 2 along score line 6, and adhesively secured thereto in the usual manner, following which the bottom sealing flap 4 is folded over the tab 2 and flap 3 and adhesively secured thereto. This operation forms the envelope for the second class mail matter.

To form the compartment for containing first class mail matter, the connecting web or strip 11

is folded downwardly along score line 14 against the reverse side of the body portion 1, as viewed in Figures 2 and 3. The body portion 8 is then folded inwardly toward said strip 11 along score line 15, whereupon the body portion 8 is then secured to body portion 1 by means of the adhesively coated portions 9 and 10. Each compartment is now in position to receive its selected contents.

Referring now to Figure 5 of the drawing, a temporary adhesive sealing member 25 for the second class compartment is placed beneath the prongs 22 and 23 of the metal fastener 24, as shown. The sealing member 25 may be of circular formation, as shown in Figures 5 and 6, rectangular formation as shown in Figure 7, or of any other suitable design or configuration. However, regardless of the design of the member 25, the same is coated with an adhesive only upon one side thereof so that the same may be adhesively secured to the closure flap 17 when the latter is folded thereover in closing relation to the several compartments of the envelope.

In operation, after the envelope has been formed to provide the several compartments, the first class mail compartment is sealed by folding the adhesively coated area 18 of the closure 17 along score line 16 over and into sealing contact with the upper portion of the body portion 1, thus leaving the remainder of the closure 17 above the score line 19 free and out of contact with the tab 2, and flap 3.

To temporarily seal the second class mail compartment so as to permit ready inspection of the contents thereof, the sealing member 25 is moistened and adhesively connected to the portion of the closure 17 above the score line 19.

When it is desired to inspect the contents of the second class mail compartment, access thereto may be readily had by merely grasping the closure 17 and pulling the same away from the envelope body. This action causes the bendable prongs 22 and 23 of the metal fastener 24 to yield inwardly toward each other and to be pulled through the opening in the sealing member. To reclose the second class mail compartment after the above described inspection, the bendable prongs are then passed through the opening 21 in the closure 17 and are flattened against the outer side of the latter in the usual manner.

In the event that the envelope has not passed through an inspection prior to its receipt by the addressee, the latter may quickly open both compartments by grasping the closure 17 and with a steady pull caused the bendable prongs to move

out of engagement with the sealing member 25 and by a continued pull cause the peeling and thereby the separation of the adhesively coated area, 18, thereof from the body portion 1 without destruction of the latter.

From the foregoing description it will be understood that the temporary sealing means disclosed in Figures 5, 6 and 7 is not restricted in its use to the form of the envelope disclosed, as it 10 will be readily apparent that same can be used on envelopes or other containers of the single or multiple compartment type without departing from the spirit of the invention or the scope of the subjoined claims.

Having thus described my invention, I claim:

1. An envelope of the character described, including a body having an open pocket therein, a closure flap carried by the body and having an opening therethrough, a bendable fastener secured to said body and having a part of a size to be passed through said opening and to be bent over said flap so as to secure the flap in covering relation to the pocket, a second fastener detachably connected to the body by initially bending over said part into contact therewith, in which position said part is in non-flap engaging and securing position with respect to said flap, and means for securing the second fastener to the flap so as to hold the same in covering relation to the pocket when the first fastener is in said non-flap engaging and securing position.

2. A device of the character described in accordance with claim 1, in which the second fastener includes a flexible element having an adhesive on one face thereof.

3. A device of the character described in accordance with claim 1, in which the second fastener includes a body having an opening therethrough and having an adhesive on one face thereof.

4. An envelope of the character described, including a body having an open pocket therein, a closure flap carried by the body, a bendable fastener secured to the body for engaging and securing the flap in covering relation to the latter, a second fastener detachably connected to the body by initially bending over the first fastener into contact with the second fastener, in which position the first fastener is in its non-flap engaging and securing position, and means for securing the second fastener to the flap so as to hold the same in covering relation to the pocket when the first fastener is in said non-flap engaging and securing position.
